UNITED STATES PATENT OFFICE

CHARLES W. MUELLER, OF ST. LOUIS, MISSOURI, ASSIGNOR TO LEWIS INVISIBLE STITCH MACHINE COMPANY, OF ST. LOUIS, MISSOURI, A CORPORATION OF MAINE

NEEDLE THREAD CONTROLLING MECHANISM

Application filed July 24, 1930. Serial No. 470,491.

This invention relates to new and useful improvements in blind stitch sewing machines generally and more particularly to a needle thread controlling mechanism therefor.

Heretofore in blind stitch machines of the well known Lewis type, the needle thread is led through a stationary tension device, thence downwardly through a stationary 10 thread guide, thence downwardly through a spring controller, and back through the guide, and thence downwardly to the needle. It is desirable to have the spring controller of sufficient strength to resist the drag of the 15 needle sufficiently and thereby maintain the thread in the needle groove during the penetrating stroke of the latter. During the retracting movement of the needle the stitch is being set and the drag of the needle thread is 20 sufficient to flex the controller upwardly. The resistance of this spring controller during the setting of each stitch is such that when sewing extremely thin fabrics the latter become 25 puckered.

Therefore the principal object of my invention is to provide a controlling device for the needle thread which will be moved positively in a direction towards the stationary guide during the retracting or stitch setting 30 movement of the needle to thereby reduce the resistance of the controller and avoid puckering of the fabrics.

Another object of my invention lies in the provision of a cam-actuated lever for positively operating the spring controller in one direction and a spring for returning the lever whereby the controller will remain in its normal or un-moved position during the penetrating stroke of the needle so as to permit 40 the controller to exert sufficient drag on the thread to maintain said thread in the needle groove.

With these and other objects in view which will more fully appear, the nature of the invention will be more clearly understood by following the description, the appended claims, and the several views illustrated in the accompanying drawings.

In the drawings:

Figure 1 is a front elevation of the stitch-

ing head and work presenting mechanism of a blind stitch sewing machine equipped with my invention,

Figure 2 is a rear elevation thereof,

Figure 3 is an elevation partly in section taken on the opposite side of the head from Figure 2,

Figure 4 is a detail elevation partly in section showing the thread controller spring and the cam-actuated lever therefor, and

Figure 5 is a detailed sectional view taken on the line 5—5 of Figure 4.

Like reference numerals designate corresponding parts throughout the several figures of the drawings.

Referring to the drawings, I have shown my invention as applied to a blind stitch sewing machine of the well known Lewis type which includes an overhanging arm 5, a stitching head 6, and a work presenting mechanism 7. Fixed to the head 6 is a stationary presser foot 8 and cooperating with the presser foot and located below the same is the work presenting mechanism 7 which includes the usual work clamp 9, 4-motion feed dog 10 and vertically reciprocable plunger 11, the latter being movable through the usual opening (not shown) formed in the presser foot 8 for cooperation with an oscillatory threaded needle 12 which is located above the presser foot. The needle 12 is fixed to a needle arm 13 which is oscillated through a driving connection 14 from the main shaft 15 journaled in the overhanging arm 5. A complementary stitch forming mechanism cooperates with the needle 12 to form a line of stitches, and as shown this complementary stitch forming mechanism includes a rotary hook 16 which is mounted on a shaft 17, the latter being driven by a vertical shaft 18 through the medium of a "2 to 1" coupling 19 from a gear 20 which is driven from the main shaft 15 through the medium of a "1 to 1" coupling 21. Thus the hook 16 rotates twice to each revolution of the main shaft 15, or in other words, twice to each complete oscillation of the needle 12. The needle thread T which is led from its supply through a stationary disc tension device 22 which is disposed above the needle 12, thence

downwardly through a stationary thread guide 23, thence downwardly through a spring controller 24, thence upwardly through the vibratory take-up 4, and thence 5 downwardly to the needle 12. The stationary thread guide 23 is formed by an opening located in a substantially U-shaped arm 25 which is rigidly attached to a post 26 which extends laterally from the stitching head, and 10 is secured to said post by a screw 27. Supported by the post 26 and arranged between the upper and lower arms of the U-shaped thread guide is the thread controller 24. This controller is formed of spring wire and 15 has one end coiled around the post 26 and secured thereto. The free end of the wire is bent into a thread guide which is disposed below the thread guide 23. The normal tendency of the spring controller 24 is to 20 move downwardly toward the needle and away from the stationary thread guide 23.

The above construction is embodied in certain of the Lewis blind stitch machines, and when the needle begins its retracting movement to set the previously formed stitch the 25 drag of the needle thread will overcome the inherent inelasticity or tension of the controller 24 and pull said controller upwardly. This has been found to create a puckering to 30 very thin fabrics and I have therefore provided means for overcoming this objection.

To this end, I have provided a cam-actuated lever 28 for positively elevating the 35 spring controller 24 during the first part of the retracting movement of the needle so as to reduce the drag on the needle thread while the previously formed stitch is being set. This lever 28 is fulcrumed intermediate its ends as at 28a to the stitching head 6. One 40 end of the lever is disposed directly under and in engagement with the spring controller 24 and the other end of the lever carries a cam roller 29 which engages a cam 30 having diametrically opposed concentric and eccentric 45 portions 31 and 32 respectively. The lever 28 intermediate its ends is provided with an arm 33 to which one end of a coil spring 34 is connected, the other end of the spring being connected to the stitching head 6. The 50 spring 34 functions to return the lever 28 to its normal position and also to yieldably retain the roller 29 in engagement with the cam 30. The cam 30 is fixed to a shaft 35 and this shaft is driven through a worm coupling 36 from the vertically disposed hook operating 55 shaft 18. The gear ratio of the coupling 36 is such that the cam shaft 35 rotates once to each revolution of the main shaft 15, and consequently the movement of the cam lever 60 28 is timed with the oscillations of the needle.

In operation assuming the needle to be at the far end of its penetrating stroke and about to be retracted, the spring controller 24 and the lever 28 are disposed in their normal positions. At this time the cam roller 29 is

about to ride on the eccentric portion 32 of the cam. Upon rotation of the main shaft 15 the needle will begin its retracting movement to set the previously formed stitch, and simultaneously therewith the eccentric portion 32 of the cam will oscillate the lever 28 and thereby positively raise or flex the spring controller 24 and thereby reduce the drag of the needle thread which would otherwise occur, and cause the previously formed stitch to 70 be set without effecting any puckering action to the material being sewed. When the needle is at the other extreme position of movement and partakes of its forward or penetrating stroke, the concentric portion 31 of the cam 30 prevents the lever 28 from being moved and consequently the inherent spring in the controller 24 will place sufficient drag on the needle thread to maintain said thread in the groove of the needle until after the hook has 80 picked up the needle thread loop.

It is of course to be understood that the details of structure and arrangements of parts may be variously changed and modified without departing from the spirit and 90 scope of my invention.

I claim:—

1. A needle thread controlling mechanism for blind stitch sewing machines comprising in combination, an oscillatory threaded needle and a complemental stitch forming mechanism, a stationary needle-thread tension device, a spring needle-thread controller and guide between the tension device and the needle and normally movable in a direction away from the needle by the needle thread action during retracting movements of the needle, and means for positively flexing the spring controller towards the tension device during each retracting movement of the needle to reduce the tension on the needle thread during the setting of the stitches.

2. A needle thread controlling mechanism for blind stitch sewing machines comprising in combination, an oscillatory threaded needle and a complemental stitch forming mechanism, a stationary needle-thread tension device, a spring needle-thread controller and guide between the tension device and the needle and normally movable in a direction away from the needle by the needle thread action during retracting movements of the needle, and means including a cam-operated lever for positively flexing the spring controller towards the tension device during each retracting movement of the needle to reduce the tension on the needle thread during the setting of the stitches.

3. A needle thread controlling mechanism for blind stitch sewing machines comprising in combination, an oscillatory threaded needle and a complemental stitch forming mechanism, a stationary needle-thread tension device, a spring needle-thread controller and 125

guide between the tension device and the needle and normally movable in a direction away from the needle by the needle thread action during retracting movements of the needle, and means for positively flexing the spring controller towards the tension device during each retracting movement of the needle to reduce the tension on the needle thread during the setting of the stitches, said means

10 comprising a lever having one end located directly under the spring controller and engaging the same, a cam engaging the opposite end of the lever, and a spring for retaining the lever in engagement with the cam.

15 4. A needle thread controlling mechanism for blind stitch sewing machines comprising in combination, an oscillatory threaded needle having a thread groove and a complementary stitch forming mechanism, a stationary

20 needle-thread tension device, a spring needle-thread controller and guide between the tension device and the needle and normally movable in a direction away from the needle by the needle thread action during retracting

25 movements of the needle, and means for positively flexing the spring controller towards the tension device during each retracting movement of the needle to reduce the tension on the needle thread during the setting of

30 the stitches, said means comprising a lever having one end located directly under the spring controller and engaging the same, a cam engaging the opposite end of the lever, and a spring for retaining the lever in en-

35 gagement with the cam, the cam permitting the spring controller to return to and remain in its normal position during the latter part of the penetrating stroke of the needle to maintain sufficient drag on the needle thread

40 and thereby retain the latter in the needle groove.

In testimony whereof I affix my signature.
CHARLES W. MUELLER.
